(57) **CLAIM**

The ornamental design for a closed pocket wrench, as shown and described.

DESCRIPTION

The present application is related to concurrently filed, co-pending U.S. Design patent application Ser. No. 29/311,316 presented by Thomas Wesley Debow and titled Open Pocket Wrench.

FIG. 1 is a front, top and side perspective view of a closed pocket wrench showing the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.
